Patented May 9, 1972

223,593

LENS CLUSTER UNIT FOR PHOTOPRINTING

Richard M. Artz, 3092 Silverton Road NE.,
Salem, Oreg. 97308

Filed May 28, 1970, Ser. No. 23,198

Term of patent 14 years

Int. Cl. D16—03

U.S. Cl. D61—1

FIG.5

FIG.2

FIG.3

FIG.1

FIG.4

FIG.6

FIG. 7

FIG. 8

FIG. 10

FIG. 9

FIG. 1 is a top plan view of a lens cluster unit for photoprinting showing my new design;

FIG. 2 is a side elevational view thereof;

FIG. 3 is a front elevational view thereof;

FIG. 4 is a rear elevational view thereof;

FIG. 5 is a bottom plan view thereof;

FIG. 6 is a top plan view of another form of my new design wherein the unit has 3 lens in place of the 2 lens of FIG. 1;

FIG. 7 is a side elevational view thereof;

FIG. 8 is a front elevational view thereof;

FIG. 9 is a rear elevational view thereof; and

FIG. 10 is a bottom plan view thereof.

I claim:

The ornamental design for a lens cluster unit for photoprinting, as shown and described.
